METHOD OF FORMING LAMP MOUNTINGS

Erwin E. Franz, Cranford, N. J., assignor to Western Electric Company, Incorporated, New York, N. Y., a corporation of New York

Original application November 3, 1950, Serial No. 193,921, now Patent No. 2,698,461, dated January 4, 1955. Divided and this application September 12, 1951, Serial No. 246,193

1 Claim. (Cl. 29—155.5)

This invention is a division of my copending application Serial No. 193,921, filed November 3, 1950, now Patent No. 2,698,461, issued January 4, 1955, and relates to a method of forming lamp mountings.

The conventional lamp mountings for switchboard lamps are usually composed of frames, insulating strips, contact springs and terminals secured together by the aid of screws, and with assemblies of this nature, particularly the handling of various parts for assembly, the contact springs and/or terminals become bent, necessitating testing of the lamp assembly prior to use.

An object of the invention is to provide a highly efficient method of forming lamp mountings wherein accurate positioning of the various parts of the lamp mounting are assured.

The method of forming a lamp mounting, including an initially formed substantially U-shaped conductive element, comprises the steps of molding a hollow body of dielectric material with portions of the legs of the conductive element intermediate their ends embedded in the body, and the removal of a part of the connecting portion between the legs of the conductive element to produce spaced terminals.

Other objects and advantages will be apparent from the following description when considered in conjunction with the drawings wherein:

Fig. 1 is a vertical sectional view of the apparatus by the aid of which the method may be practiced, the view being taken through the parting lines of the companion members of the apparatus;

Fig. 2 is a vertical sectional view taken along the line 2—2 of Fig. 1;

Fig. 3 is a side elevational view of the lamp mounting;

Fig. 4 is a longitudinal sectional view of the completed lamp mounting;

Fig. 5 is a sectional view taken along the line 5—5 of Fig. 3; and

Fig. 6 is a top plan view of the apparatus.

Referring now to the drawings, attention is first directed to Figs. 3, 4, and 5, illustrating the lamp mounting. The completed lamp mounting includes a body 10 molded of a dielectric material made hollow through the central portion thereof while one end 11 is formed to receive a switchboard lamp. Aligned apertures 12 are formed in the body intermediate the ends thereof to receive the inner ends 14 of spring contacts which are initially formed of a single resilient element, indicated generally at 15 in Fig. 2, which is substantially U-shaped in general contour. The outer end of the element is bent as shown in Fig. 2 so that when a part of the connecting portion 16 is removed by the aid of a punch or any other suitable means, there will remain inwardly bent ends 17. A laterally extending projection 18, formed integral with the body 10 must be disposed at either of two positions, one of which is shown in the drawing and the other position being at the left of that shown in Fig. 3, so that the projections of adjacent lamp mountings may overlap or be positioned above and below, if so desired.

2

The apparatus, by the aid of which the method may be practiced for forming the lamp mounting, is shown in Figs. 1, 2, and 6, and includes companion mold members 20 and 21 having substantially like recesses or apertures to form a mold cavity. Only the recesses of the mold member 20 are shown in the drawings, but it should be understood that the description of these recesses and their identifying reference numerals apply also to the recesses of the other member 21. The main recess or cavity 23 extends longitudinally of the mold member 20 to receive the main core 24. The core 24 has an end portion 25 removably mounted in a plug 26, threadedly disposed in a base 27. The base 27 may be supported on its lower surface 28 or either one of the diagonally extending surfaces 29 or 30. A member 32 of the main core forms the outer portion of the cavity to receive a switchboard lamp. The intermediate portion of the main core 24 has diametrically opposed pairs of recesses 34 and 35 to receive adjacent portions of the legs of the U-shaped conductive element 15 to automatically locate and accurately hold the element in position during molding of the body of insulating material. The upper portion 36 of the main core 24 completes the central cavity of the molded body.

The members 20 and 21 have aligned apertures 38 and 39 to receive core members 40 and 41 which fill the apertures and have recesses 42 and 43 in their inner ends to surround the adjacent portions of the legs of the conductive element 15 to cooperate with the main core 24 in the formation of the apertures 12 in the body 10 of the lamp mounting.

The formation of the projection 18 in the position shown in Figs. 3 and 5, or in the other position referred to in the foregoing description, is under the control of companion cavities 45 in the mold members 20 and 21 and the position of a reversible core 46. It will be noted that the cavity 45 is twice the thickness of the projection 18, half of this area being filled by the projection 47 of the core member 46, determining the location of the projection 18 of the body 10. The core member 46 is in the position to form the projection 18 at the present position, but if the core member 46 should be reversed, locating the projecting portion 47 thereof at the bottom of the cavity instead of at the top thereof, the projection 18 would be located at its other position. A pin 50 supported in the threaded plug 26 and extending upwardly into recesses 51 of the mold members 20 and 21 and also through an aperture 52 of the projecting portion 47 of the core 46 serves as a core to form the aperture 53 in the projection 18 regardless of the position this projection is formed on the body 10.

The mold members 20 and 21 are provided with recesses 56 and 55, combining to form the gate for the molten material when poured into the mold, the gate entering the main cavity at the bottom of the mold. The mold members 20 and 21 are removably secured together by screws 58 or the like, while the core members 40 and 41 are removably held in the position shown by suitable means such as springs 60 and 61.

Considering now the method by the aid of the apparatus shown in the drawings, the conductive element 15 is located on the main core member 24 with the lower ends of the leg members entering their respective recesses 35 while other portions of the leg members enter the recesses 34 to thereby readily and accurately locate the conductive element for molding in the body 10 of the lamp mounting. The core member 46 is located at the desired position in either one of the mold members 20 and 21, after which these mold members, with the core 46 in position, are located adjacent each other on the base so that the core pin 50 will extend through the aperture 52 of the core member 46. The mold members 20 and 21 may then be secured together and the core members

40 and **41**, either at this time or prior to the securing of the mold members **20** and **21**, together may be inserted in their respective apertures back of their springs. The core members **40** and **41** will seal their respective portions of the mold against the material to form the apertures **12** in the body of the lamp mounting. To start the molding of the body, the apparatus may be tilted, if desired, to rest upon the surface **30** while the molten material is poured into the gate and allowed to travel first to the bottom of the cavity and then fill the cavity to complete formation of the body **10**. When the material has solidified or cooled properly, the base **17** may be rotated with respect to the plug **26**, moving against the mold members **20** and **21** to remove the main core member **24** together with the core pin **50** from the molded body **10**. The cores **40** and **41** may then be removed and the mold members **20** and **21** separated for the removal of the molded structure therefrom. The final step of the method for forming the lamp mounting includes the removal of a part of the **20** connecting portion **16** of the conductive element **15** to complete spaced line contact elements and terminals **18** in the molded body of the lamp mounting.

It is to be understood that the above described arrangements are simply illustrative of the application of the **25** principles of the invention. Numerous other arrangements may be readily devised by those skilled in the art which will embody the principles of the invention and fall within the spirit and scope thereof.

What is claimed is:

The method of forming a lamp mounting including an initially formed substantially U-shaped resilient conductive element, the method comprising molding an elongate body of dielectric material with an aperture to removably receive a lamp extending longitudinally therein from one end thereof and with laterally extending apertures open to the lamp receiving aperture flexing the free resilient leg portions outwardly while molding the body, whereby portions of the legs of the conductive element intermediate their ends will be embedded in the body, with the free resilient leg portions normally disposed mainly in the laterally extending apertures and partially in the lamp receiving aperture to removably grip a lamp therebetween, and removing a part of the connecting portion between the legs of the conductive element to produce spaced electrical contacts.
